UNITED STATES PATENT OFFICE

144,355

DESIGN FOR A CALCULATOR FOR RADIO SIGNALING

William Carduner and Lawrence Le Kashman,
New York, N. Y., assignors to Multi Slide
Instrument Corp., Chicago, Ill., a corporation
of Illinois

Application August 8, 1945, Serial No. 121,319

Term of patent 14 years

(CL. D52—1)

To all whom it may concern:

Be it known that we, Lawrence Le Kashman and William Carduner, citizens of the United States and residents of the county of Nassau, city and State of New York, with post office addresses respectively at 261 Central Avenue, Lawrence, Long Island, New York, have invented a new, original, and ornamental Design for a Calculator for Radio Signaling, of which the following is a specification, reference being had to the accompanying drawing, forming part thereof, in which:

Fig. 1 is a front view of a calculator for radio signaling showing our new design.

Fig. 2 is a rear view of the same.

Fig. 3 is an end elevation of the same.

We claim:

The ornamental design for a calculator for radio signaling, as shown.

WILLIAM CARDUNER.
LAWRENCE LE KASHMAN.
